FLOOR POLISHING MACHINE

Edward L. Verhagen, Rahway, N. J., assignor to The
Regina Corporation, Rahway, N. J., a corporation of
New York

Application July 29, 1954, Serial No. 31,654

Term of patent 14 years

(Cl. D9—2)

To all whom it may concern:

Be it known that I, Edward L. Verhagen, a citizen of the United States of America and resident of Rahway, county of Union, State of New Jersey, have invented a new, original, and ornamental Design for a Floor Polishing Machine, of which the following is a specification, reference being had to the accompanying drawing, forming a part thereof, in which:

Fig. 1 is a front view of a floor polishing machine embodying my design;

Fig. 2 is a side view thereof; and

Fig. 3 is a rear view thereof.

I claim:

The ornamental design for a floor polishing machine, substantially as shown.
